(57) **CLAIM**

The ornamental design for a solar roller blind, as shown and described.

DESCRIPTION

FIG. 1 is a front elevational view of a solar roller blind showing my new design;

FIG. 2 is a rear elevational view thereof;

FIG. 3 is a left side view thereof;

FIG. 4 is a right side view thereof;

FIG. 5 is a top plan view thereof;

FIG. 6 is a perspective view thereof;

FIG. 7 is a second perspective view thereof;

FIG. 8 is a third perspective view thereof;

FIG. 9 is a fourth perspective view thereof; and,

FIG. 10 is a fifth perspective view thereof.

The evenly spaced broken lines depict portions of the solar roller blind that form no part of the claimed design.

The dot dash dot broken lines in the drawings denote the boundaries of the claim and form no part thereof.

1 Claim, 10 Drawing Sheets
